UNITED STATES PATENT OFFICE.

ISAAC APPELBAUM, OF PHILADELPHIA, PENNSYLVANIA.

FABRIC-CUTTING MACHINE.

1,310,853.

Specification of Letters Patent. Patented July 22, 1919.

Application filed January 30, 1919. Serial No. 274,008.

To all whom it may concern:

Be it known that I, ISAAC APPELBAUM, a subject of the King of Great Britain, having resided in the United States one year last 5 past and having declared my intention of becoming a citizen thereof, residing in the city and county of Philadelphia, State of Pennsylvania, have invented a new and useful Fabric-Cutting Machine, of which the 10 following is a specification.

My invention relates to a fabric cutting machine, and consists of a reciprocating blade therefor, the same being adapted to be guided in its movement in a retaining member 15 of the machine and is provided with spring tongues which project from said blade beyond the side face thereof and are adapted to be independently guided in the movement of the blade in said member by 20 means additional to and independent of the means adapted to guide the body of the blade, whereby the blade is doubly guided and so is adapted to run true and smooth without lost motion and without rattling in 25 its movements throughout its entire range of action.

The invention is satisfactorily illustrated in the accompanying drawing, but the important instrumentalities thereof may be 30 varied, and so it is to be understood that the invention is not limited to the specific details shown and described, as long as they are within the spirit or scope of the claims.

Figure 1 represents a side elevation of a 35 portion of said blade and adjacent members of a fabric cutting machine embodying my invention.

Fig. 2 represents a side elevation of said cutter, and adjacent members of the 40 machine, a portion of the guide and retainer for the blade having been removed.

Fig. 3 represents a vertical section on line 3—3 Fig. 1.

Fig. 4 represents a top or plan view of a 45 portion of the machine with the blade removed therefrom.

Fig. 5 represents a horizontal section on line 5—5 Fig. 1.

Fig. 6 represents a side elevation of a portion of the blade having cutting edges different from those shown in Fig. 2.

Similar numerals of reference indicate corresponding parts in the figures.

Referring to the drawings.

1 represents a horizontally extending bracket which is connected with the adjacent

portion of the frame of a fabric cutting machine, which latter is well known in the art.

Extending downwardly from said bracket 60 and connected therewith is the vertically extending leg 2, the lower end of which has thereon the foot 3 which is screwed or otherwise connected with the base 4, thus firmly sustaining said leg in position. 65

In said leg is the vertically extending runway or passage 5 which is adapted to receive the reciprocating blade 6, the cutting edge of which is adapted to project forwardly from the front of said leg so as to be adapted to cut the fabric placed on the base, said blade being adapted to be connected at its upper end with the slide head 7 of the machine, whereby it receives motions in opposite directions, and so effects the cutting 75 operation.

On the inner walls of the runway are the channels 8 which are in communication with said runway, as most plainly shown in Fig. 4, the purpose of which will be hereinafter 80 described.

The blade is formed of a flat piece of steel or other suitable metal on the sides of which are the curved tongues 9 which are punched out of said piece and so integral at one end 85 with said piece while their bodies extend outwardly disconnected and salient from the sides of the piece and so are resilient in their nature, and they alternate on opposite sides of the blade, it being seen that the blade is 90 inserted in the leg 2 and mainly occupies the runway 5 while the tongues 9 occupy the channels 8, both tongues and blade being adapted to move freely in their respective positions while being operated by the slide 95 head 7.

It will be seen also that while the blade rides freely in contact with the walls of the runway the tongues 9 ride freely in contact with the walls of the channels 8, but 100 owing to the resilient nature of said tongues the latter press frictionally and resiliently against said walls of the channels, and so cause the blade to avoid lost motion and move true, steady and smooth and without 105 rattling in the runway. Further, the sides of said tongues are angular in form and the walls of said channels are similarly shaped so that the walls of the channels freely inclose the tongues as most plainly shown in 110 Fig. 5, whereby the tongues and the blade are prevented from turning and so the blade

is controlled whereby it is steadied in its motions and so the cutting of the fabric will be exact and uniform without any possible irregularity, throughout the entire length of the blade. The blade has a plurality of cutting edges either of which may be placed in front, the tongues being intermediate of said edges, and the ends of the blade are each formed with an eye or opening whereby either end may be connected with the slide head 7, the blade being reversible for said purpose, it being adapted also to be inserted into the runway at the bottom thereof on the underside of the base.

Where it is desired to cut rubber or other tough fabrics the cutting edges of the blade are made serrated as at 11, Fig. 6, instead of smooth as shown in the other figures, but the blade is provided with the tongues 9, the same as shown in said other figures.

Having thus described my invention what I claim as new and desire to secure by Letters Patent, is:—

1. In a reciprocating blade for a fabric cutting machine, a resilient tongue thereon projecting from the side face thereof, said tongue being integral at one of its ends with said blade.
2. A reciprocating blade for a fabric cutting machine having thereon a row of resilient tongues, the latter projecting laterally from said blade beyond the side face thereof, said tongues being each connected at one end with said blade and having its

other end and sides disconnected from the blade.

3. In a fabric cutting machine, a guide and retainer for a blade of the machine, said blade having on a side thereof a resilient tongue which is adapted to project laterally from said side, and said guide having therein a runway for said blade, and a channel in a wall of said runway for said tongue, said blade and tongue being freely movable in said runway and channel respectively. 45

4. In a fabric cutting machine, a blade having on its side a resilient tongue out-turned therefrom and integral therewith, and said machine having a guide and retainer for said blade having within it a runway in which said blade is movable and a channel in the wall of said runway in which said tongue is movable. 50

5. A blade for a fabric cutting machine provided on the side thereof with a resilient tongue which is adapted to project laterally from said side and said machine having a guide and retainer for said blade provided with a runway in which said blade is movable, and a channel in the wall of said runway in which said tongue is movable, the walls of said channel freely inclosing said tongue. 55

ISAAC APPELBAUM.
